UNITED STATES PATENT OFFICE.

BENJAMIN B. TROMBLEY, OF SYRACUSE, NEW YORK.

WAGON.

Application filed July 7, 1922. Serial No. 573,365.

To all whom it may concern:

Be it known that I, BENJAMIN B. TROMBLEY, a citizen of the United States, residing at Syracuse, in the county of Onondaga and State of New York, have invented new and useful Improvements in Wagons, of which the following is a specification.

This invention relates to toys, and more particularly to a foot propelled wagon, and 10 comprehends a novel construction of means whereby children of tender age can conveniently use the toy and propel it over the ground or surface with the expenditure of a minimum of effort.

15 The nature and advantages of the invention will be better understood when the following detailed description is read in connection with the accompanying drawing, the invention residing in the construction, combination, and arrangement of parts as claimed.

20 In the drawing forming part of this application, like numerals of reference indicate similar parts in the several views, and 25 wherein:

Figure 1 is a perspective view of the wagon constructed in accordance with the invention.

Figure 2 is a sectional view taken on line 30 2-2 of Figure 1.

Figure 3 is a sectional view taken on line 3-3 of Figure 1.

Referring to the drawing in detail, 10 indicates the body of the wagon, while the front wheels are indicated at 11 and the rear wheels indicated at 12. The front wheels 11 are journaled on an axle 13 which is pivoted as at 14 so that the wagon can be conveniently guided. Projecting from 35 the axle 13 is an extension 15 which is slotted as at 16, and pivoted in this slot is one end of a tongue or handle 17, so that the latter can be grasped by the user to steer the wagon. The rear wheels 12 are journaled in suitable brackets 18 which project 40 rearwardly from the wagon body and preferably of U-shaped formation in cross section. Depending from the wagon body adjacent one of these bearings, but between 45 said bearings is a step 19, which may be of any suitable construction.

Projecting rearwardly from the wagon body and slightly spaced from one of the 50 said bearings is a wall or partition 20, and journaled upon said partition and the adjacent bearings is a shaft 21. Carried by

one end of this shaft is an arm 22 which supports a pedal 23, the latter being disposed adjacent the step 19, so that it can be engaged by one foot of the user to rotate the 60 said shaft, while the other foot of the user occupies the step 19. In this manner, the shaft is rotated, and carried by the shaft for rotation therewith, is an internal gear 65 24. The axle for the adjacent rear wheel 11 carries a pinion 25 which meshes with the teeth of the internal gear, so that as the latter is rotated, motion is imparted to the rear axle, and the wagon propelled with the expenditure of a minimum amount of effort. 70 In use, the user places one foot upon the step 19, and the other foot upon the pedal rotating the shaft with the latter mentioned foot in the manner above described, while the wagon is conveniently steered or guided 75 by means of the handle which can be swung upon its pivot in the direction of the user.

While it is believed that from the foregoing description, the nature and advantages of the invention will be readily apparent, I 80 desire to have it understood that I do not limit myself to what is herein shown and described, and that such changes may be resorted to when desired as fall within the 85 scope of what is claimed.

What I claim is:

1. A toy wagon comprising a wagon body, front and rear wheels, means for guiding the wagon, bearings projecting rearwardly from the wagon body for said rear wheels, a step depending from the rear of the wagon body and arranged adjacent one of said bearings, a partition projecting from the wagon body and arranged in juxtaposition to the other bearing, a shaft journaled between said partition and the adjacent bearing, foot operated means for rotating said shaft, and gearing connecting the said shaft with the axle of the adjacent wheel for the purpose specified. 90 95 100

2. A toy wagon comprising a wagon body, front and rear wheels, means for guiding the wagon, bearings projecting from the rear of the wagon for said rear wheels, a step depending from the wagon and disposed adjacent one of said bearings, a partition projecting from the wagon and arranged in juxtaposition to the other bearing, a shaft journaled between the partition and said bearing, an arm projecting from said shaft, a pedal carried by said arm for rotating said shaft, and a gearing connecting the 105 110

shaft with the axle of the adjacent rear wheel for the purpose specified.

3. A wagon comprising a wagon body, front and rear wheels, means for steering said wagon, bearings projecting from the rear of the body for said rear wheels, a step depending from the wagon body adjacent one of the bearings, a partition projecting from the wagon and arranged adjacent the other bearing, a shaft journaled

in said partition and the latter mentioned bearing, foot operated means for rotating said shaft, an internal gear carried by the shaft, and a pinion carried by the axle of the adjacent wheel and meshing with said gear for the purpose specified. 15

In testimony whereof I affix my signature.

BENJAMIN B. TROMBLEY.
